UNITED STATES PATENT OFFICE.

S. BRYAN JEROME, OF NEW HAVEN, CONNECTICUT.

SHAFT FOR STEAMSHIPS.

SPECIFICATION forming part of Letters Patent No. 294,878, dated March 11, 1884.

Application filed August 20, 1883. (No model.)

To all whom it may concern:

Be it known that I, S. BRYAN JEROME, a citizen of the United States of America, residing at New Haven, in the county of New Haven and State of Connecticut, have invented 5 certain new and useful Improvements in Shafts for Steamships, of which the following is a specification, reference being had therein to the accompanying drawings.

10 My invention relates to shafts, and has particular reference to such when used in extended lengths, as on shipboard and in other situations. Long shafts are used on steamers and in many other situations where the strain upon 15 it in ordinary use or in case of shocks is such as to require a yielding power in the shaft, which will enable it to spring and give and not break when subjected to strains. The ordinary shafting does not possess this required 20 property, and it is the object of this invention to produce an article which does. I construct a shaft of strands of straight wires laid parallel and wrapped with a wire or wires wound spirally around said strands. By this construction I avail myself of the strength of the 25 straight wires and the capacity for bending without injury which a number of united parts of small diameter possess, as contradistinguished from a single piece of the same diameter as that of the several parts united, and at the same time take advantage of the tensile 30 strength of the spiral coils and their power to hold the straight wires in place. I arrange the spirally-wrapped strands about a central 35 core in layers to preserve the circular form, and wrap each of these layers in a spirally-wound coil, so as to produce a yielding case or envelope over each layer of strands. One of the cases or envelopes thus made forms the 40 exterior surface of the shaft. I then shrink on bearings and give additional strength by placing clamps upon the shaft at intervals.

The accompanying drawings illustrate what I consider the best means of carrying the invention into practice.

45 Figure 1 shows a shaft broken away at both ends made in accordance with the invention herein set forth. This figure also shows the journals set upon the shaft at intervals. Fig. 50 2 is a cross-section of the shaft, and Fig. 3 is a perspective view of a clamp which can be used upon the shaft.

In all the figures where they occur, similar letters of reference indicate corresponding parts.

55 A is the core or center around which the exterior portions are built. This core may be a round bar of iron, a pipe, or tube of suitable size—say from one to three inches in diameter; or it may, as shown, be composed of a 60 bundle or strand of straight wires wrapped in a spiral coil of wire of single thickness or more from end to end. About this core I place a course of collections or bundles of straight wires, B, in such a manner as to preserve the circular form. Each of the bundles 65 B is wrapped in a spiral coil of a thickness of wire. After these strands are laid in place, I encircle the whole in a spiral coil in a similar way to that described for the single strands. 70 This envelope is marked C. Around this envelope may be superposed another line of strands, as B', made like those marked B, and over this line another wrapping of wire, (indicated at C') which in the shaft shown in the 75 drawings forms the exterior surface of the shaft; but, if desired, I may continue to add course after course of strands and wrap them in an envelope of spirally-wound wire, according to the size of the strands or the required 80 diameter of the shaft; or, in cases where one layer of strands will make the shaft large and strong enough, the subsequent layers may be omitted.

85 Upon the shaft, at required intervals, may be shrunk journals, as shown at D. These strengthen the shaft, and at the same time afford means for sustaining the shaft upon bearings. Where it is not convenient to place one 90 of these journals D, or when by wear or accident the shaft becomes torn or weakened, a clamp, as E, Fig. 3, may be placed around it. This of course may be done when the journals are not used with the necessary frequency, whether the shaft has become injured at that 95 point or not.

Having thus described my invention, what I desire to claim and secure by Letters Patent is—

1. A shaft composed of straight wires wrapped in spiral coils of wire having journals, substantially as herein set forth.
2. In a shaft, the combination, with a core, A, of a layer or layers of collections of straight

wires placed around the core, each collection being separately wrapped in a spiral coil, substantially as herein set forth:

3. A shaft composed of a core, A, a layer of layers of collections of straight wires, each collection being wrapped in a spiral coil of wire; and a wrapping of spirally-wound wire around each layer of collections, substantially as herein set forth.

In testimony whereof I affix my signature in the presence of two witnesses.

S. BRYAN JEROME
